Primary Examiner — Ricky Pham(57) **CLAIM**

The ornamental design for a blade guide handle, as shown and described.

DESCRIPTION

FIG. 1 is a perspective view of a blade guide handle showing interior inserts between edge inserts;

FIG. 2 is a perspective view thereof, omitting the interior inserts for easy of disclosure;

FIG. 3 is a front of a blade guide handle showing interior inserts;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a perspective view of a handle of the blade guide handle;

FIG. 10 is a front view thereof;

FIG. 11 is a side view of an edge insert of the blade guide handle; and,

FIG. 12 is a perspective view showing the blade guide handle in use with a cutting container.

The broken line showing interior inserts in FIG. 1, FIG. 3-FIG. 8, and FIG. 12, and the broken line showing a cutting container in FIG. 12, is included for the purpose of illustrating environmental structure and forms no part of the claimed design.
